UNITED STATES PATENT OFFICE

BYERS W. KADEL, OF BALTIMORE, MARYLAND, ASSIGNOR TO THE SYMINGTON COMPANY, OF NEW YORK, N. Y., A CORPORATION OF MARYLAND

CAR TRUCK

Application filed April 6, 1926. Serial No. 100,141.

This invention relates to railway car trucks and especially to the construction of side frames and the associated spring plank, bolster and spring plates together with the arrangement of a six or seven unit nest of springs cooperating therewith whereby increased truck capacity is secured.

The principal object of the invention, generally considered, is the improvement in design of the side frames, bolster, spring plank and spring plates whereby a greater number of springs than normally employed may be utilized without radically changing the construction of the various parts.

15 An object of the invention is the employment of a nest of springs comprising six units hexagonally arranged in place of the standard five group nest of springs for supporting the bolster on the truck side frames, 20 said nest being employed either with or without a central single coil spring whereby increased truck capacity is secured, the side frames, bolster, spring plank and spring plates being modified for efficiently accomplishing the desired result.

Another object of the invention is the design of side frames, bolster, spring plank and cooperating spring plates for permitting the employment of an additional spring unit 30 with each side frame, said spring unit together with the standard five units being arranged in the form of an equilateral hexagon with a long axis thereof disposed longitudinally of the side frame with which it is employed, thereby making it possible to use a spring plank not materially increased in length, the spring plank seat portions of the side frames being so constructed and reinforced by stools or columns that an adequate 35 area of sufficient strength is provided for properly supporting the spring plank and its associated springs, spring plates and bolster.

A further object of the invention is to increase the capacity of railway car trucks employing standard five unit nests of springs 45 for supporting the bolster with respect to the associated side frames, by using an additional spring unit arranged with six spring units in hexagonal form, the complete nest of springs 50 being disposed with a long axis of the hexa-

gon substantially coinciding with the longitudinal axis of the side frame whereby the springs balance about the longitudinal center line of the side frame, the spring plank being necessarily widened at its ends to allow for 55 the increased corresponding dimension of the nest of springs, but being of approximately standard length because the dimension of the nest of springs longitudinally of the spring plank is not very much increased, the bolster 60 being preferably of nearly standard construction.

A still further object of the invention is the provision of a six group nest of springs for supporting each end of a truck bolster 65 whereby the capacity of the truck with which employed is increased, said springs replacing the A. R. A. standard five group nest of springs normally employed with seventy ton trucks and being positioned with respect 70 to the side frames so that the center of gravity of each nest lies on the longitudinal center line of the associated frame, the six units of the nest of springs being arranged as an equilateral hexagon with a long axis disposed 75 in line with the longitudinal axis of the side frame, the associated spring plates being correspondingly formed and provided with centrally disposed cupped portions adapted for receiving retaining means of a shorter length 80 than normal thereby obviating the necessity for forming apertures for said retaining means in the associated spring plank and frame, said cupped portions being adapted 85 for receiving and positioning a centrally disposed single coil spring in addition to the six units of the nest of springs for further increasing the truck capacity, said spring plates being also formed with locating bosses arranged on the longitudinal center line of 90 gravity of the plates, said bosses being adapted for reception in positioning apertures of standard location in the associated spring plank, said spring plank being of approximately standard length but correspondingly 95 widened at its ends for receiving the correspondingly enlarged nest of springs and formed with bosses at its ends for limiting the shifting of said springs, those portions 100 of the bolster guide columns of the side frame

adjacent the nearest springs being formed with spring clearance cuts therein whereby it is possible to employ an otherwise standard bolster opening in the side frame.

5 Other objects and advantages of the invention relating to the particular arrangement and combination of the individual parts will become apparent as the description proceeds.

Referring to the drawings illustrating my 10 invention, the scope whereof is defined by the appended claims:

Figure 1 is a partial side elevation of a truck, shown partly in section and with parts omitted, and particularly showing the construction of the various members associated with the bolster springs.

Figure 2 is a fragmentary horizontal sectional view on the line 2—2 of Figure 1 looking in the direction of the arrows.

20 Figure 3 is a transverse sectional view on the line 3—3 of Figure 1 looking in the direction of the arrows.

Figure 4 is a plan of the spring plank seat portion of the side frame, the position of 25 the springs thereover being indicated diagrammatically by dot and dash lines.

Figure 5 is a top plan of the bottom spring plate and is likewise a bottom plan of the top spring plate.

30 Referring to the drawings in detail, like parts being designated by like reference characters, a truck side frame 1 is shown fragmentarily and said frame, in the embodiment illustrated, is of integral cast construction 35 comprising a compression member 2, a tension member 3, and bolster guide columns or struts 4 spacing intermediate portions of said compression and tension members, leaving a window or bolster opening therebetween.

40 The compression member 2, over the bolster opening, is illustrated as of substantially channel or inverted U shape in cross section, the bolster guide columns 4 are shown of similar construction at the bolster guiding 45 portions thereof, while the tension member 3, beneath the bolster opening 5, is preferably generally box shape in cross section and formed with an upper web 6, a lower web 7, a front or outer web 8 and a rear or inner web 9, said webs 8 and 9 being preferably

50 upright or vertical beyond the bolster opening but being formed outwardly flaring or sloping from the side edges of the lower web 7 to the upper web 6 beneath the bolster opening. In order to form a spring plank seat portion of ample width, the web 6 is extended laterally beneath the bolster opening forming outward or front flange or shelf portions 10 beyond the web 8 and inward or rear flange or shelf portions 11 beyond the web 9.

55 In the embodiment illustrated, the spring plank 12 rests directly on the upper web 6 of the tension member which forms the seat-

60 portion therefor, the upper surface of 65

said spring plank seat portion is preferably provided with A. R. A. standard squaring lugs 13 which engage in corresponding apertures 14 in the spring plank for maintaining the desired relation between the parts. The 70

end of the spring plank 12 is necessarily wider than standard because of the spring arrangement employed, but the spring plank may be made from a plate of standard width by making the upstanding flanges at the ends 75

of the spring plank of a height reduced in accordance with the increased width thereof. The length of the spring plank may be approximately the same as that of a standard spring plank but the ends of said plank are otherwise slightly different for reasons to be pointed out hereinafter. As shown most

clearly in Figures 1 and 2, the spring plank is of channel or U construction and the lower web thereof is formed with spring plate locating apertures 15 positioned so that when 80

the spring plank is assembled with the side frames the apertures are located on the longitudinal center line thereof.

Figure 3 is a transverse sectional view on the line 3—3 of Figure 1 looking in the direction of the arrows.

20 Figure 4 is a plan of the spring plank seat portion of the side frame, the position of the springs thereover being indicated diagrammatically by dot and dash lines.

Figure 5 is a top plan of the bottom spring plate and is likewise a bottom plan of the top spring plate.

30 Referring to the drawings in detail, like parts being designated by like reference characters, a truck side frame 1 is shown fragmentarily and said frame, in the embodiment illustrated, is of integral cast construction 35 comprising a compression member 2, a tension member 3, and bolster guide columns or struts 4 spacing intermediate portions of said compression and tension members, leaving a window or bolster opening therebetween.

40 The compression member 2, over the bolster opening, is illustrated as of substantially channel or inverted U shape in cross section, the bolster guide columns 4 are shown of similar construction at the bolster guiding 45 portions thereof, while the tension member 3, beneath the bolster opening 5, is preferably generally box shape in cross section and formed with an upper web 6, a lower web 7, a front or outer web 8 and a rear or inner web 9, said webs 8 and 9 being preferably

50 upright or vertical beyond the bolster opening but being formed outwardly flaring or sloping from the side edges of the lower web 7 to the upper web 6 beneath the bolster opening. In order to form a spring plank seat portion of ample width, the web 6 is extended laterally beneath the bolster opening forming outward or front flange or shelf portions 10 beyond the web 8 and inward or rear flange or shelf portions 11 beyond the web 9.

55 In the embodiment illustrated, the spring plank 12 rests directly on the upper web 6 of the tension member which forms the seat-

60 portion therefor, the upper surface of 65

said spring plank seat portion is preferably provided with A. R. A. standard squaring lugs 13 which engage in corresponding apertures 14 in the spring plank for maintaining the desired relation between the parts. The 70

end of the spring plank 12 is necessarily wider than standard because of the spring arrangement employed, but the spring plank may be made from a plate of standard width by making the upstanding flanges at the ends 75

of the spring plank of a height reduced in accordance with the increased width thereof. The length of the spring plank may be approximately the same as that of a standard spring plank but the ends of said plank are otherwise slightly different for reasons to be pointed out hereinafter. As shown most

clearly in Figures 1 and 2, the spring plank is of channel or U construction and the lower web thereof is formed with spring plate locating apertures 15 positioned so that when 80

the spring plank is assembled with the side frames the apertures are located on the longitudinal center line thereof.

Figure 3 is a transverse sectional view on the line 3—3 of Figure 1 looking in the direction of the arrows.

20 Figure 4 is a plan of the spring plank seat portion of the side frame, the position of the springs thereover being indicated diagrammatically by dot and dash lines.

Figure 5 is a top plan of the bottom spring plate and is likewise a bottom plan of the top spring plate.

normally used with seventy ton trucks. The arrangement of springs shown can just be slid into place beneath a standard bolster and between the bolster guides of the standard side frame opening. The clearance, however, is not sufficient for operation and cylindrical clearance cuts, pockets or recesses 22 are, therefore, provided at the lower ends of the bolster guiding portions of the columns 10, 4, these cuts extending up, as illustrated particularly in Figure 1, just slightly above the bottom face of the bolster, or the top face of the spring group so that they do not materially reduce the bearing area where the bolster rubs against the wearing faces of the side frame.

Because of the short axis of the nest of springs being arranged longitudinally of the spring plank, said spring plank may be made 20 of substantially standard length because of the very slight increase in dimension of the spring group along the short axis thereof over the standard five unit nest of springs. Instead of the single boss normally employed 25 on each end of the spring plank for limiting outward shifting of the nest of springs, I preferably employ two bosses 23, disposed as indicated particularly in Figure 2, so as to cooperate with the four outermost spring units. 30 The locating bosses 17 are so arranged with respect to the collars 19 that the springs balance about said bosses, that is, said bosses lie preferably on the longitudinal center line 35 of gravity of said springs so that, when engaged in the locating apertures 15 in the spring-plank 12, the springs balance about the longitudinal center line of the frame.

The upper spring plate 24 may be constructed identical with the lower spring plate 40 16 but is reversed so that the collars 19 extend downwardly and engage the inner springs 20 and the locating bosses 17 extend upwardly and engage in corresponding apertures, not shown, in the truck bolster 25. Because of the positioning of the springs as 45 previously referred to, the truck bolster need not be extended any great distance to provide for the reception of the nest of springs. It is preferable, however, to increase the thickness of the web 26 at 27 where the same is 50 extended horizontally to take care of the corresponding increased dimension of the nest of springs so as not to appreciably decrease the strength of the bolster at this point.

55 For retaining the spring plates 16 and 24 in the desired assembled relation with respect to the springs therebetween, and placing said springs under any desired initial compression or stress, the central portions of the spring plates are cupped or embossed toward each other, as indicated at 28, said cupped portions being perforated at 29 for receiving a retaining bolt or other means 60 for extending therebetween. The portions 28 of the spring plates are formed sufficiently deep

to enable a short enough bolt 30 to be employed so as not to necessitate perforating the associated spring plank and side frame for receiving said bolt when the springs are compressed under load. In other words, the plates may be cupped sufficiently to allow for using a retaining bolt, the length of which is the same or less than the solid height of the springs. The diameter of the cupped portions 28 preferably corresponds with the inner diameter of the single coil spring 21 so that said cupped portions are adapted for receiving and positioning said additional coil spring. If desired, the customary retaining bolt apertures may be formed in the spring 70 plank and side frames so that the nest of springs constructed in accordance with my invention may be replaced by an A. R. A. standard five unit nest of springs, the spring 75 plank 12, however, if formed with retaining 80 bosses 23, positioned as shown, not being 85 adapted for receiving a normally positioned standard nest of springs.

For adequately reinforcing the spring 90 plank seat or upper web 6 of the tension member 3 with respect to the novel arrangement of springs in accordance with my invention, said web 6, which is increased to its greatest width directly beneath the innermost and outermost pairs of spring units 18, is reinforced 95 in addition to the reinforcing action secured by the diverging webs 8 and 9 beneath the outermost and innermost pairs of spring units, by preferably angular columns or stools 100 31, 32 and 33 located preferably directly beneath the springs lying along the longitudinal center line of the side frame and extending between the lower web 7 and the upper web 6. In the embodiment illustrated, these 105 columns or stools are shown + or as star shape in cross section, but it is obvious that I do not wish to be restricted to the exact showing thereof. The end columns 31 and 33 lie, respectively, under the spring units of the six 110 group nest of springs which lie on the longitudinal center line of the frame whereas the intermediate supporting column 32 lies directly under the single coil central spring 21. From a consideration of Figure 4, it will be 115 seen that the side webs 8 and 9 of the tension member are almost ideally located for supporting the two pair of spring units positioned most inwardly and outwardly of the side frame as the centers of said spring units lie almost directly over the upper edges of 120 said webs while the stools or columns 31, 32 and 33 are similarly located for supporting the other springs. Although the aforescribed reinforcement is especially designed for the six or seven unit group of springs 125 arranged in accordance with my invention, yet it is admirably adapted for supporting the A. R. A. standard five unit nest of springs when the same is normally positioned with 130 respect to the side frame.

From the foregoing description, it will be apparent that I have provided a construction which gives a twenty per cent or greater increase in spring capacity without radically changing the construction of the side frames, 5 spring plank and associated bolster. With said modified members, the A. R. A. standard five group nest of springs may be employed interchangeably with the spring arrangement disclosed if the embossments or bosses 23 on 10 the spring plank 12 are omitted and said plank and the side frames are provided with apertures underlying the spring plate retaining means for receiving said means upon compression of the springs. When using the standard 15 five group nest of springs, for example, if such is necessary when making repairs, there will, of course, be slightly more clearance at the place of engagement of the bolster therewith and the bolster will overhang to a 20 greater extent than with the present arrangement. In the same way, the spring plank, if used with the standard arrangement of springs, will be slightly wider than is absolutely necessary. 25

Having now described my invention, what I claim is:

1. In a car truck, in combination, a side frame formed with a bolster opening and a 30 spring plank seat portion beneath said opening, a spring plank positioned on said seat portion, a six unit nest of springs supported on said spring plank above the seat portion of the frame, said springs being arranged 35 in hexagonal form and disposed so that a long axis of the nest corresponds with the longitudinal center line of the frame, an additional single coil spring centrally disposed with respect to the six unit nest of springs, 40 spring plates disposed above and below the nest of springs, and means passing through said single coil spring and connecting said plates for holding the parts of the nest of springs assembled.

45 2. In a car truck, in combination, a side frame formed with a compression member, a tension member and bolster column guides spacing intermediate portions of said compression and tension members and leaving a window opening therebetween, the portion 50 of the tension member, beneath the window opening, being laterally widened to form a spring plank seat, a spring plank supported on said seat, a six unit nest of springs supported on said spring plank and arranged in hexagonal form with a long axis thereof disposed longitudinally of the side frame, said spring plank being correspondingly widened 55 at its end to accommodate the nest of springs, 60 said springs arranged on said spring plank so that the center of gravity of the group lies on the longitudinal center line of the side frame and a single coil spring centrally disposed with respect to said six unit nest of 65 springs on said spring plank, a bolster, the

corresponding end of which is supported by the springs, and retaining means for said springs serving to properly space the same with respect to each other, the spring plank and bolster.

3. In a car truck, in combination, a side frame formed with a bolster opening and a spring plank seat portion beneath said opening providing a supporting surface at substantially uniform elevation, a spring plank 75 positioned on said supporting surface, a six unit nest of springs, hexagonally arranged with a long axis thereof disposed longitudinally of the frame, supported on said spring plank above the seat portion of the frame, all of said spring units being of standard size and each comprising an inner and an outer coil, and the spring plank being correspondingly widened at its end on account of the increased corresponding dimension of 80 the nest of springs but formed of approximately standard length because of the dimension of the nest of springs along the length of the spring plank being only slightly increased, and a seventh standard outer coil 85 disposed centrally of said nest of springs to increase the capacity thereof while allowing sufficient room for the desired retaining means.

4. In a car truck, in combination, a side frame formed with a compression member, a tension member and bolster guide columns spacing intermediate portions of the compression and tension members and leaving a window opening therebetween, that portion 95 of the tension member, beneath the window, opening being laterally widened to form a spring plank seat portion, a spring plank supported on said seat portion, a six unit nest of springs supported on said spring plank, said springs being arranged with their units disposed as an equilateral hexagon with a long axis thereof extending longitudinally of the frame and with the spring plank widened over the spring plank seat portion to 100 correspond with the supported nest of springs, a bolster, the corresponding end of which is supported by the springs, spring plates positioned one above and one below said springs and cupped toward each other at the center of the spring arrangement and retained by a bolt passing through the cupped portions of said plates, said cupped portions being sufficient in depth to permit compression of the springs without the necessity of providing an aperture in the spring plank to 105 correspond with the retaining bolt, an additional single coil spring positioned centrally of the six unit nest of springs and held in place by the cupped portions of the spring plates, the spring plank outwardly of some of the springs being formed with retaining bosses for limiting spring shifting with respect to the plank.

110 5. In a car truck, in combination, a side 115 frame formed with a compression member, a tension member and bolster column guides spacing intermediate portions of said compression and tension members and leaving a window opening therebetween, the portion of the tension member, beneath the window opening, being laterally widened to form a spring plank seat, a spring plank supported on said seat, a six unit nest of springs supported on said spring plank and arranged in hexagonal form with a long axis thereof disposed longitudinally of the side frame, said spring plank being correspondingly widened at its end to accommodate the nest of springs, 120 said springs arranged on said spring plank so that the center of gravity of the group lies on the longitudinal center line of the side frame and a single coil spring centrally disposed with respect to said six unit nest of springs on said spring plank, a bolster, the

125 5. In a car truck, in combination, a side

frame formed with a bolster opening and a spring plank seat portion beneath said opening, a six unit hexagonally arranged nest of springs supported on said spring plank seat portion, spring plates disposed one above and one below said springs and provided with locating bosses on the center line of the frame and adapted for engagement with corresponding apertures of standard location, said 10 bosses being disposed on long axes of the spring plates, said spring plates being also cupped toward each other centrally of the spring arrangement whereby they may be connected together by a retaining bolt shorter than normal, thereby allowing sufficient room 15 for compression of the springs without perforating the spring plank for the reception of said bolt, said cupped portions being of a size adapted to receive a single coil spring 20 between said spring plates.

6. In a car truck, in combination, a side frame formed with a bolster opening and a spring plank seat portion beneath said opening, a spring plank positioned on the seat 25 portion of the frame, a hexagonally arranged six unit nest of springs supported on said spring plank above said seat portion and disposed with a long axis of the nest in line with the longitudinal center line of the frame, 30 spring plates for said springs, said plates being formed with securing means extending between central portions thereof, said central portions being cupped toward each other and adapted for receiving an additional single 35 coil spring therearound, and substantially conical locating bosses on said plates adapted to engage in standard apertures on the center line of the frame.

7. In a car truck, in combination, a side 40 frame formed with a compression member, a tension member and bolster guide columns spacing intermediate portions of said compression and tension members and leaving a window opening therebetween, that portion 45 of the tension member, beneath the window opening, being widened to form a spring plank seat portion, a spring plank supported on said seat portion, a six unit nest of springs supported on said spring plank over the seat 50 portion, said spring units being arranged as an equilateral hexagon with the long axis thereof arranged longitudinally of the side frame, a bolster, the corresponding end of which is supported by the springs, spring 55 plates positioned, respectively, above and below said springs and provided with spring positioning flanges for the six units of the nest of springs and central cupped portions adapted for receiving an additional single 60 coil spring and extending toward each other, said cupped portions being apertured, means extending through said apertures for holding said spring plates in position with respect to said springs, said plates being provided 65 with substantially conical locating bosses ar-

ranged for engaging in normally located apertures in the bolster and spring plank, respectively, the side frame being of standard window opening size with bolster columns provided with cuts therein for providing sufficient clearance with respect to the adjacent 70 spring units.

8. In a car truck, in combination, a side frame formed with a compression member, a tension member and bolster column guides 75 spacing intermediate portions of said compression and tension members and leaving a bolster opening therebetween, that portion of the tension member, beneath the bolster opening, being generally box shape in cross section with an upper relatively wide web forming a spring plank seat portion, a lower web narrower than said upper web, webs extending upwardly and outwardly from the side edges of said lower web to the upper web 80 beneath the spring seat portion gradually converging at their upper ends to substantially upright positions beyond the spring seat portion, a spring plank supported on said upper web, a six unit nest of springs supported on said spring plank and arranged as an equilateral hexagon with its center of gravity 85 lying on the longitudinal center line of the side frame and its long axis coinciding with said center line, an additional single coil 90 spring positioned on said spring plank and centrally disposed with respect to the other springs, the spring seat portion of the side frame being reinforced for properly supporting the springs lying along the longitudinal center line of the side frame by columns 95 angular in cross section extending between the upper and lower webs of the tension member directly beneath said springs.

9. In a car truck, in combination, a side 100 frame formed with a compression member, a tension member and bolster guide columns 105 spacing intermediate portions of said compression and tension members and leaving a bolster opening therebetween, the portion of the tension member, beneath the bolster opening, being formed generally box shape in cross section with an upper relatively wide web 110 serving as a spring plank seat portion and adapted for supporting a spring plank upon which rests a six unit nest of springs hexagonally arranged with its long axis disposed longitudinally of the side frame, the upper web of said box section being widened from beyond the bolster column members and extended at a maximum width beneath the two outermost spring units and the two innermost spring units of the nest of springs and reinforced beneath said springs by the side webs of 115 the box section of the tension member being 120 gradually flared outwardly from the lower web to the upper web so that beneath said inner and outer spring units said webs join with the upper web of the tension member substantially directly beneath the centers of said spring 125 130

units, and additional reinforcing means beneath the remaining spring units comprising stools angular in cross section extending from the lower web to the upper web directly beneath said springs.

5 10. In a car truck, in combination, a side frame formed with a bolster opening of standard size and a spring plank seat portion beneath said opening, and a six unit nest 15 of standard springs supported at a uniform elevation by said spring plank seat portion of the side frame, said springs being arranged in substantially regular hexagonal form with a long axis of said nest arranged longitudinally of the side frame, the nest being positioned so as to balance about the longitudinal center line of the side frame, those portions of the frame at the sides of the bolster opening and nearest the springs being 20 provided with clearance recesses for said springs.

11. In a car truck, in combination, a side frame formed with a compression member, a tension member and bolster guide columns 25 spacing intermediate portions of the compression and tension members and leaving a window opening therebetween, that portion of the tension member, beneath the window opening, being laterally widened to form a 30 spring plank seat portion, a spring plank supported on said seat portion, a six unit nest of springs supported on said spring plank, said springs being arranged with their units disposed as an equilateral hexagon with a long 35 axis thereof extending longitudinally of the frame and with the spring plank widened over the spring plank seat portion to correspond with the supported nest of springs, a bolster, the corresponding end of which is 40 supported by the springs, spring plates positioned one above and one below said springs and cupped toward each other at the center of the spring arrangement and retained by a bolt passing through the cupped portions 45 of said plates, said cupped portions being sufficient in depth to permit compression of the springs without the necessity of providing an aperture in the spring plank to correspond with the retaining bolt.

50 12. In a car truck, in combination, a side frame formed with a compression member, a tension member and bolster column guides 55 spacing intermediate portions of said compression and tension members and leaving a bolster opening therebetween, that portion of the tension member, beneath the bolster opening, being generally box shape in cross section with an upper relatively wide web forming a spring plank seat portion, a lower web, webs extending upwardly and outwardly from the side edges of said lower web to the upper web beneath the spring seat portion, a spring plank supported on said upper web, a six unit nest of 60 springs supported on said spring plank and 65 springs supported on said spring plank and

arranged as an equilateral hexagon, the spring seat portion of the side frame being reinforced for properly supporting the springs lying along the longitudinal center line of the side frame by columns extending between the upper and lower webs of the tension member.

70 13. In a car truck, in combination, a side frame formed with a compression member, a tension member and bolster guide columns 75 spacing intermediate portions of said compression and tension members and leaving a bolster opening therebetween, the portion of the tension member, beneath the bolster opening, being formed generally box shape 80 in cross section with an upper relatively wide web serving as a spring plank seat portion and adapted for supporting a spring plank upon which rests a six unit nest of springs 85 hexagonally arranged with its long axis disposed longitudinally of the side frame, the upper web of said box section being widened from beyond the bolster column members and extended at a maximum width beneath the two outermost spring units and the two innermost spring units of the nest of springs 90 and reinforced beneath said springs by the side webs of the box section of the tension member being gradually flared outwardly from the lower web to the upper web so that beneath said inner and outer spring units 95 said webs join with the upper web of the tension member substantially directly beneath the centers of said spring units.

14. A side frame for railway car trucks 100 comprising a compression member, a tension member and bolster guide columns spacing intermediate portions of said compression and tension members and leaving a window opening therebetween, that portion of the frame, beneath the window opening, being formed generally box shape in cross section with an upper relatively wide web serving as a spring plank seat portion, a lower web narrower than said upper web and side webs extending between the side edges of said lower web and the upper web, said upper web being reinforced at its widened portion by having the side webs flared outwardly under the spring plank seat portion, said upper web 110 being additionally reinforced at the spring plank seat portion by spaced columns extending between the upper and lower webs thereof.

115 15. A side frame for railway car trucks 120 comprising a compression member, a tension member and bolster guide columns spacing intermediate portions of said compression and tension members and leaving a window opening therebetween, that portion of the frame, beneath the window opening, being formed generally box shape in cross section with an upper relatively wide web serving as a spring plank seat portion, said web being 125 formed with standard spring plank squaring 130

lugs on its upper surface, a lower web narrower than said upper web and side webs extending between the side edges of said lower web and the upper web, said upper web being reinforced at its widened portion by having the side webs gradually flared outwardly so that under the spring plank seat portion the upper edges of said side webs are substantially parallel with the side edges of the upper web, said upper web being additionally reinforced at the spring plank seat portion by a plurality of longitudinally spaced columns lying along the longitudinal center line of the frame and extending between the upper and lower webs thereof.

16. A spring plate for a six unit spring group formed with a central cupped portion perforated for the reception of retaining means for said group and adapted to position an additional spring, and annular spring centering flanges hexagonally disposed around said cupped portion.

17. A spring plate for a six unit spring group formed with a central cupped portion perforated for the reception of retaining means for said group and adapted for receiving a single coil spring therearound, annular spring centering flanges hexagonally disposed around said cupped portion and spaced substantially conical locating bosses disposed on said plate on a long center line thereof and adapted for engagement in apertures positioned for standard spring plates.

18. In a car truck, in combination, a side frame formed with a compression member, a tension member and bolster guide columns spacing intermediate portions of said compression and tension members and leaving a bolster opening therebetween, the portion of the tension member, beneath the bolster opening, being formed generally box shape in cross section with an upper relatively wide web serving as a spring plank seat portion and adapted for supporting a spring plank upon which rests a six unit nest of springs hexagonally arranged with its long axis disposed longitudinally of the side frame, the upper web of said box section being widened and extended at a maximum width beneath the two outermost spring units and the two innermost spring units of the nest of springs, and the sides of said box section extending upwardly from the lower web meet the upper web substantially directly beneath said outermost and innermost springs.

19. In a truck, in combination, a side frame with a bolster opening and a spring plank seat portion beneath said opening, a spring plank of approximately standard length supported on said seat portion, a seven unit nest of springs supported on said spring plank, six of said units being standard double coil springs and the seventh a single coil spring, a bolster supported on said nest of springs, said spring plank seat portion being disposed

in a single plane, the double coil spring units being arranged in the form of a regular hexagon with the seventh single coil spring centrally disposed and three spring units positioned along the longitudinal center line of the side frame, whereby when the bolster angles with respect to the spring plank the eccentricity of the force applied to said nest of springs is maintained at a minimum.

20. In a truck, in combination, a side frame formed with bolster guide columns, a bolster opening of standard size therebetween and a spring plank seat portion lying at a single elevation beneath said opening, a spring plank supported directly on said spring plank seat portion, a single spring plate supported on said plank, a six unit nest of springs resting on said spring plate, said nest of springs comprising six spring units arranged in regular hexagonal form with two of said units disposed directly along the longitudinal center line of the side frame, said spring plank seat portion being of normal length with the lower ends of the columns normally disposed, the lower ends or guide portions thereof terminating below the tops of the springs and formed so as to properly guide an associated bolster, being formed with pockets adjacent said springs to provide the necessary clearance.

In testimony whereof I affix my signature.
